Howard C. Thompson
ATTORNEY

UNITED STATES PATENT OFFICE.

CHARLES H. KESSLER, OF RICHMOND HILL, NEW YORK, ASSIGNOR TO SOSS MANUFACTURING COMPANY, OF BROOKLYN, NEW YORK, A CORPORATION OF MAINE.

HINGE.

Application filed June 1, 1926. Serial No. 112,916.

This invention relates to hinges of the invisible type and particularly to hinges constructed for use in the mounting of the doors of motor vehicles or which may be used for any purpose; and the object of the invention is to provide one of the butts of a hinge of the class specified with means for reinforcing and strengthening a predetermined portion thereof and further to provide a stop 10 for limiting the outward movement of the door; a further object being to provide a hinge, one of the butts of which is fashioned from sheet metal and consists of two substantially L-shaped parts coupled together by the pintle pin employed and further coupled together by a reinforcing sheet metal member of yoke-shaped form in cross section positioned on said parts of the butt adjacent the outer end portion thereof and 15 in spaced relation with reference thereto and which may also extend onto the pintle pin portion of said parts and partially form the bearing for said pin by the passage of the pin therethrough; and with these and other objects in view, the invention consists 20 in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in 25 each of the views, and in which:

Fig. 1 is a sectional view through a part of a door and door frame showing my improved hinge mounted in connection therewith and with part of the construction 30 broken away and in section.

Fig. 2 is a partial section on the line 2—2 of Fig. 1.

Fig. 3 is a sectional plan view of the construction as seen in Fig. 1 of the drawing 40 but showing the door in an open position.

Fig. 4 is a view similar to Fig. 1 but showing only part of a hinge and showing a modification.

Fig. 5 is a view looking in the direction 50 of the arrow 5 in Fig. 4, with part of the hinge broken away, and in section; and,

Fig. 6 is a view similar to Fig. 5, but showing parts in full section, and showing a modification.

In the drawing, I have indicated at 10 a 55 part of a door frame and at 11 a part of a door, and mounted in connection with one side face of the door 11 is a hinge member 12 in the form of a hook-shaped arm having an attaching plate portion 13 adapted 60 to be secured to the door, and the hook end 14 of the arm extending outwardly with reference to the outer swinging of the door and being arranged within the boundaries 65 of the side edge of the door in connection with which it is mounted or within the boundaries of the door frame as seen. The outer end 14 of the butt 12 is provided with an aperture 15 in which the pintle pin 16 secured to the other butt 17 of the hinge 70 is mounted.

The butt 17 in the construction shown is composed of two similar butt parts 18 and 19, L-shaped in cross sectional form and comprising attaching plate portions 18^a and 19^a and pintle bearing portions 18^b and 19^b, which in the construction of the butt are directed inwardly into the door frame and are in parallel relation with each other and coupled together by the pintle pin 16 which 80 is secured thereto or to laterally projecting ears 18^c and 19^c on the parts 18^b and 19^b.

In practice, I provide the parts 18^b and 19^b adjacent the ears 18^c—19^c and also adjacent the attaching plate parts 18^a—19^a 85 with notches 20 to receive the crosshead portion 21 of a yoke-shaped reinforcing member 22, the ends 23 of said member extending in parallel relation and overlying the pintle bearing parts 18^b and 19^b of the hinge 90 butt 17 as clearly seen in Figs. 1 and 2 of the drawing, and being riveted or otherwise secured as seen at 24 to said parts 18^b and 19^b. By providing the notches 20, the outer face of the crosshead 21 of the member 22 95 will lie flush with the corresponding edges of the separate parts of the butt as clearly seen in Fig. 1 of the drawing, but this structure is not absolutely necessary as the feature of my invention resides in the provision of a reinforcing member which will serve 100 to strengthen the butt 17 or the parts 18 and

19 thereof adjacent the attaching plate portions 18^a and 19^a and also to provide a stop member for limiting the outward swinging movement of the door 11 as seen in Fig. 3 of the drawing, it being understood that the position of the crosshead portion 21 on the member 22 will control and regulate the swinging movement of the door and may be adjusted to suit the required conditions.

10 In Figs. 4 and 5 of the drawing, I have shown a slight modification, wherein I have substituted for the member 22 a reinforcing member 25 also of yoke-shaped cross sectional form, and the crosshead 26 of this member is wider than the crosshead 21 of the member 22 as clearly seen in Fig. 4 of the drawing. The end portions 27 are of such form as to correspond with the contour of the pintle bearing portions 18^b and 19^b of a hinge butt. It is also preferred that the projecting ears 28 formed on the end portions 27 to correspond with the ears 18^c and 19^c will have apertures 29 to receive the pintle pin 16 whereby said pin will be provided with a greater bearing surface and will also serve to secure the reinforcing member 25 to the hinge butt. However, other means may also be employed if desired, to aid in securing the parts together as by welding as indicated at 30 in Figs. 4 and 5 of the drawing.

15 The crosshead 26 of the member 25 also functions as a stop and further provides a substantial side wall for the hinge butt 17 or the pintle bearing portions 18^b and 19^b thereof.

20 A hinge constructed in the manner described may be made strong and durable in a simple, economical and effective manner, and in addition to the reinforcement of the hinge butt, the reinforcing member employed also serves as a stop for limiting the swinging movement of the door, the same being secured in position in such manner as to provide the required or necessary swing of the door member. While I have shown certain details of construction for carrying my invention into effect, it will be understood that I am not necessarily limited to the structure herein shown and described, and various changes therein and modifications thereof may be made within the scope of the appended claims without departing from the spirit of my invention or sacrificing its advantages.

25 In Fig. 6 of the drawing, I have shown another modification wherein a yoke-shaped butt body 31 similar in general contour to the member 26, seen in Figs. 4 and 5, is provided as the main member of the hinge butt. Secured to the outer faces of the side members 32 of the butt body 31 are L-shaped butt parts 33 comprising attaching plate portions 34 and pintle bearing portions 35. The pintle bearing portions 35

are similar to the side portions 32 of the body 31, the latter also forming pintle bearing portions as will be apparent, it being understood that the portions 32 and 35 are of the general contour, in plane, as the pintle bearing portions of the parts 18-19 and 26 in Figs. 4 and 5 of the drawing. The parts 33 are secured to the body 31 by riveting or otherwise as seen at 36.

20 Having fully described my invention, what I claim as new and desire to secure by Letters Patent, is:—

25 1. In a hinge, a hinge butt composed of two butt parts L-shaped in cross sectional form and comprising attaching plate portions, and pintle bearing portions, and means formed independent of said butt parts and secured to the bearing portions adjacent the plate portions for reinforcing said parts and coupling the same together.

30 2. In a hinge, a hinge butt composed of two butt parts L-shaped in cross sectional form and comprising attaching plate portions and pintle bearing portions, means formed independent of said butt parts and secured thereto for reinforcing the same, said means comprising a U-shaped member the crosshead of which transverses the space between the pintle bearing portions of said butt parts adjacent said plate portions and secured to said pintle bearing portions.

35 3. In a hinge, a hinge butt composed of two butt parts L-shaped in cross sectional form and comprising attaching plate portions and pintle bearing portions, means formed independent of said butt parts and secured thereto for reinforcing the same, said means comprising a U-shaped member the crosshead of which transverses the space 40 between the pintle bearing portions of said butt parts and mounted upon adjacent faces of said pintle bearing portions, said pintle bearing portions having apertures to receive the pintle pin of the hinge, and said member having apertures corresponding with said first named apertures.

45 4. In a hinge, a hinge butt composed of two butt parts L-shaped in cross sectional form and comprising attaching plate portions and pintle bearing portions, means formed independent of said butt parts and secured to the bearing portions adjacent the plate portions for reinforcing said parts and coupling the same together, said means comprising a U-shaped member the crosshead of which transverses the space between the pintle bearing portions of said butt parts adjacent said plate portions and the crosshead portion of said reinforcing member forming a stop for limiting the movement 50 of the other butt of the hinge in one direction.

5. In a concealed hinge, one of the butts of which is composed of two independent and

substantially L-shaped sheet metal parts arranged in spaced relation and coupled together by a pintle pin of the hinge, a U-shaped reinforcing member secured to the 5 separate parts of the butt and having a crosshead portion transversing the space between said parts.

6. In a concealed hinge, one of the butts of which is composed of two substantially L-shaped sheet metal parts arranged in spaced relation and coupled together by a pintle pin of the hinge, a reinforcing member secured to the separate parts of the butt and having a crosshead portion transversing the space 10 between said parts and serving to couple said parts together and retain the same in spaced relation and to provide a stop for limiting the movement of the other butt of the hinge in one direction.

15 7. In a concealed hinge, one of the butts of which is composed of two substantially L-shaped sheet metal parts arranged in spaced relation and coupled together by a pintle pin of the hinge, a reinforcing member secured 20 to the separate parts of the butt and having a crosshead portion transversing the space between said parts and serving to couple said parts together and retain the same in spaced relation and to provide a stop for 25 limiting the movement of the other butt of the hinge in one direction, and said reinforcing member having portions through which the pintle pin is adapted to pass.

30 8. A hinge butt of the class described comprising two independent parts having pintle bearing portions arranged in spaced relation and having apertures for receiving the pintle pin of the hinge and laterally extending attaching plate portions, and a stop 35 wall member formed independent of and secured to said parts transversing the space between the adjacent faces of the pintle bearing portions of the butt and arranged adjacent the attaching plate portions of said 40 butt.

45 9. A hinge butt of the class described comprising two independent parts having pintle bearing portions arranged in spaced relation and having apertures for receiving the 50 pintle pin of the hinge and laterally ex-

tending attaching plate portions, a stop wall transversing the space between the adjacent faces of the pintle bearing portions of the butt and arranged adjacent the attaching plate portions of said butt, and the side portion thereof having the pintle pin apertures. 55

10. In a hinge, a hinge butt composed of two independent butt parts, and a third U-shaped part for coupling the first named parts together and supporting the same in 60 spaced relation, with the flat surfaces of the ends of the U-shaped part in parallel relation to corresponding surfaces of the butt parts.

11. In a hinge, a hinge butt composed of 65 two independent butt parts, and a third U-shaped part for coupling the first named parts together and for supporting the same in spaced relation, said first named parts and the last named part having pintle bearing 70 portions adapted to receive and support the pintle pin of the hinge.

12. In a hinge, a hinge butt composed of two independent butt parts, and a third U-shaped part for coupling the first named parts 75 together and for supporting the same in spaced relation, said first named parts and the last named part having pintle bearing portions adapted to receive and support the pintle pin of the hinge, and the first named parts 80 having attaching plate portions.

13. In a hinge, a hinge butt composed of two independent butt parts, and a third U-shaped part for coupling the first named parts together and for supporting the same 85 in spaced relation, said first named parts and the last named part having pintle bearing portions adapted to receive and support the pintle pin of the hinge, the first named parts having attaching plate portions, and 90 the crosshead of the third U-shaped part transversing the space between the first named butt parts and forming a stop for limiting the movement of the other butt of the hinge in one direction. 95

In testimony that I claim the foregoing as my invention I have signed my name this 27th day of May, 1926.

CHARLES H. KESSLER.
